(57) **CLAIM**

The ornamental design for a micro needle sheet, as shown and described.

DESCRIPTION

FIG. 1 is a front view of a micro needle sheet showing my new design;

FIG. 2 is a rear view thereof;

FIG. 3 is a right side view thereof;

FIG. 4 is a left side view thereof;

FIG. 5 is a top view thereof;

FIG. 6 is a bottom view thereof; and,

FIG. 7 is a partially enlarged view indicating the circled area
“7” in FIG. 6.

The broken lines indicating an enlargement portion of the
design form no part of the claimed design.

The stipple on the edge of the micro needle sheet in FIG. 2
indicates an adhesive material.

1 Claim, 7 Drawing Sheets
